(57) **CLAIM**

I claim the ornamental design for a hand held vacuum cleaner, as shown and described.

DESCRIPTION

FIG. 1 is a perspective view of a hand held vacuum cleaner showing my new design;

FIG. 2 is a top view thereof;

FIG. 3 is a left view thereof;

FIG. 4 is a front end view thereof;

FIG. 5 is a rear end view thereof;

FIG. 6 is a right view thereof; and,

FIG. 7 is a bottom view thereof.
